(57) **CLAIM**

The ornamental design for a cover, as shown and described.

DESCRIPTION

FIG. 1 is a bottom front perspective view of a cover showing our new design;

FIG. 2 is a bottom rear perspective view thereof;

FIG. 3 is a top rear perspective view thereof;

FIG. 4 is a top front perspective view thereof;

FIG. 5 is a front view thereof;

FIG. 6 is a top view thereof;

FIG. 7 is a bottom view thereof;

FIG. 8 is left side view thereof; and,

FIG. 9 is a right side view thereof.

The shade lines in the Figures show contour and not surface ornamentation.

The solid line that forms the claimed innermost edge of the front of the cover and the solid line that forms the claimed innermost edge of the rear of the cover are boundaries of the claimed design. All surfaces and broken lines on the interior of the cover that are between these two solid lines form no part of the claimed design. The broken lines on the exterior of the cover that form the outermost edges of the openings represent boundaries of the claimed design and form no part of the claimed design. All other broken lines on the exterior of the cover depict unclaimed environment and form no part of the claimed design.
